UNITED STATES PATENT OFFICE.

FRANK P. FLINN, OF TERRE HAUTE, INDIANA, ASSIGNOR TO THE SAFETY CAR COUPLER COMPANY, A CORPORATION OF INDIANA.

AUTOMATIC CAR COUPLING.

Application filed February 13, 1922. Serial No. 536,237.

To all whom it may concern:

Be it known that I, FRANK P. FLINN, a citizen of the United States, residing at Terre Haute, in the county of Vigo and 5 State of Indiana, have invented new and useful Improvements in Automatic Car Couplings, of which the following is a specification.

One object of my said invention is the 10 provision of an automatic coupling designed especially for use on mine cars and so characterized that it is unnecessary for an aperture to go between cars for the coupling or uncoupling of the same.

Another object is the provision of a coupling the drawheads of which will not be connected on contact unless the coupling link is projected from its drawhead, so that 20 a loaded car may be made to bump an empty car off a "cage" without coupling.

Another object is the provision of an automatic coupling efficient on short curves and adapted to transverse curves without liability of the drawheads locking.

25 To the attainment of the foregoing, the invention consists in the improvement as hereinafter described and definitely claimed.

In the accompanying drawings, forming part of this specification:—

30 Figure 1 is a plan view of my improvement.

Figure 2 is a side elevation of the same.

Figure 3 is a horizontal section taken in the plane indicated by the line 3—3 of Figure 35 2.

Figure 4 is a longitudinal section on line 4—4 of Figure 1.

Figure 5 is a similar view which shows the opposed drawheads as connected together.

Figure 6 is a perspective of the coupling link per se.

Figure 7 is an enlarged detail perspective of the slidable body of one drawhead.

45 Figure 8 is an enlarged perspective of the pin of said drawhead.

Figure 9 is an enlarged perspective of the lever carried thereby.

Similar numerals of reference designate 50 corresponding parts in all of the views of the drawings.

The opposed ends of two cars 1 and 2 are shown in Figures 1—5.

Carried by the illustrated end of the car 55 1 is a housing 3 in which is fixed a guide

block 4 and in the outer end wall of which is a guide aperture 5.

The block 4 includes a transverse-central apertured wall 6 and sleeves 7 at opposite sides of the same.

Movable longitudinally through the wall 6 and sleeves 7 is a drawbar 8 on which is a nut or other appropriate abutment 9 between which and the wall 6 is a coiled spring 10, mounted on the bar 8. The outer 60 end of the drawbar 8 extends into the hollow shank 11 of a drawhead 12, and is connected to said shank 11 through the medium of a pin 13. Disposed in the drawhead 12 is a slidable, spring-locked body 14 in 70

which is a longitudinal slot 15 to receive a limiting pin 16, carried by the drawhead. The mouth of the drawhead 12 is flared as shown, and in the upper and lower walls of the drawhead at points adjacent to said 75 mouth are vertically-alined apertures 16 and 17 for the reception of a heavy and strong pin 18, preferably circular in cross section and provided with a reduced and flattened and apertured upper end portion 80

19. On the upper side of the drawhead 12 are parallel standards 20 between which is fulcrumed a lever 21, the outer end of which is bifurcated at 22 to straddle the pin portion 19, and is provided in the walls of 85 the bifurcation with longitudinal slots 23 to receive the pin 24 by which the lever 21 is connected to the pin 18. The pin 18 and the lever 21 are yieldingly maintained in and adapted to be placed in the positions shown 90

in Figure 5 by a strong spring 25 which bears against the upper side of the drawhead 12 and the outer arm of the lever 21, Figures 2, 4 and 5. The inner arm of the lever 21 is connected through a link 26 with 95

a crank 27 on a transverse shaft 28, journaled in appropriate bearings 29 on the end of the car body 1 and having cranks 30 at its ends, Figure 1. Manifestly when it is desired to raise the pin 18 to enable the 100 body 14 to assume a position under said pin 18, Figure 4, the same may be conveniently accomplished by an aperture standing at either side of the car or car body 1.

The drawhead 31 carried by the car or 105 car body 2 and designed to cooperate in opposed relation with the drawhead 12, is housed in and held against longitudinal movement relative to said car body 2, is provided with a chamber 32, and is also pro-

vided with a hollow shank 33, the interior of which is in communication with the chamber 32 as best shown in Figure 5. Permanently secured in the outer portion of the drawhead 31 is a strong vertical pin 34 which rests in an open coupling link 35, carried by the drawhead 31 and movable in the chamber 32 thereof from the position shown in Figures 3 and 4 to that shown in Figure 5 and vice versa. On the inner end of said link 35 is an apertured tongue 36, and pinned or otherwise connected to said tongue 36 is the slotted head 37, Figure 3, of a bar 38, the slot in the said head being of arcuate form and receiving the pin 39 so as to permit the link 35 to swing horizontally relative to the bar 38. The said bar 38 is guided for rectilinear, longitudinal movement in the shank 33 and is longitudinally slotted at 40 to receive an upstanding crank 41 on a transverse shaft 42, journaled in appropriate bearings 43 on the car body 2 and having handles 44 at its ends and at opposite sides of the said body 2. From this it follows that an operative at one side of the body 2 is enabled without going between the cars, to project the link 35—i. e., move the same from the position shown in Figures 3 and 4 to that shown in Figure 5, and this against the action of the retractile spring 45 which is interposed between and connected to the crank 41 and the car body 2. Obviously the projection of the link 35 tensions the spring 45, with the result that immediately following the release of the said link 35 from the pin 18 of drawhead 12, the said spring 45 will promptly draw the link 35 into its fully-housed position in the drawhead 31 and inwardly beyond the abutting end or face of the said drawhead 31, Figures 3 and 4.

It will be apparent from the foregoing that while the drawhead 31 has no movement relative to the car body 2, the drawhead 12 is movable longitudinally with respect to its car body 1 and is cushioned in its opposite movements by the springs 10, Figure 3. It

will also be apparent that to couple the cars it is simply necessary for an operative to project the link 35 precedent to the coming together of the drawheads, when the link 35 will engage and move inwardly the body 14, whereupon the spring-actuated lever 21 will force the pin 18 into the link 35 and complete the coupling, and this in such manner that casual uncoupling will be precluded.

It will further be noted that in virtue of my improvement it is entirely practical to couple and uncouple cars though they be standing with the drawheads 12 and 31 in contact. This obviates the heavy work involved in shifting loaded cars by hand precedent to the coupling or uncoupling thereof.

Having described my invention, what I claim and desire to secure by Letters Patent, is:—

1. In a car coupling, a draw head being equipped with a coupling link, and means extending to the side of the car body, whereby the link may be manually projected from the draw head, this means including a rectilinearly movable bar and an arcuate coupling between the outer end of said bar and the inner end of the link whereby the inner end of the link is adapted to move horizontally relative to the outer end of the bar.

2. In a car coupling, a draw head being equipped with a coupling link and means extending to the side of the car body, whereby the link may be manually projected from the draw head, this means including rectilinearly movable bar and an arcuate coupling between the outer end of said bar and the inner end of the link, whereby the inner end of the link is adapted to move horizontally relative to the outer end of the bar and also including a transverse rock shaft having handle means, and also having a crank engaging the bar, and a retractile spring interposed between and connecting the crank and the car body and tending to retract the link.

In testimony whereof, I affix my signature.

FRANK P. FLINN.
